UNITED STATES PATENT OFFICE.

CHARLES H. ALLEN AND JAMES B. ANDERSON, OF PITTSBURGH, PENNSYLVANIA.

BLOWTORCH.

1,390,265.

Specification of Letters Patent. Patented Sept. 13, 1921.

Application filed August 5, 1920. Serial No. 401,348.

To all whom it may concern:

Be it known that we, CHARLES H. ALLEN and JAMES B. ANDERSON, citizens of the United States, residing at Pittsburgh, in the county of Allegheny and State of Pennsylvania, have invented certain new and useful Improvements in Blowtorches, of which the following is a specification.

This invention relates to blow-torches, and more particularly to a torch adapted for utilizing liquefied gas as fuel.

One of the main objects of the invention is to provide a torch so constructed as to enable the use of fuel in either gaseous or liquid form, as desired.

Figure 1 is a central vertical sectional view through a torch constructed in accordance with our invention, parts being shown in elevation.

Fig. 2 is a view partly in section through the handle.

Fig. 3 is a fragmental sectional view through the standard and associated parts.

Fig. 4 is a front view of the main burner and pilot burner casing.

Fig. 5 is a section through the same.

Referring to Figs. 1 and 3, the tank 1 is provided with an opening through its top wall through which is secured, in any preferred or suitable manner a cylindrical standard 2 provided with two ducts 3 and 4 extending approximately one-third of the length of the standard. These ducts communicate, at their upper ends, with a main duct 5 extending axially of the standard, suitable valves 6 and 7 being provided for controlling communication between this main duct and the auxiliary ducts 3 and 4, respectively.

A main burner 8 is secured in the standard and communicates with duct 5 at the upper end thereof, a pilot burner 9 being positioned below the main burner and also in communication with this duct. This pilot burner is inclosed by a casing 10 depending from a perforated mixer or manifold 11 secured to the standard and extending about the main burner 8 in the known manner. An opening is provided through the top of casing 10, a suitable screen 12 being inserted in this opening, to permit lighting of the main burner from the pilot light of the pilot burner, as will be understood.

The flow of fuel from duct 5 to burner 8

is controlled by a valve 13 threaded through a nipple 15 projecting from the standard and provided adjacent its outer end with a knurled wheel 16. This valve is of tubular construction to slidably receive a tubular member 17 open at its inner end and slidably through a packing gland 18 of suitable type provided at the outer end of the valve. A knurled disk 19 is detachably secured to the outer end of member 17 by means of a central stem 20 threaded into the outer end of the same. This stem is provided with an axial bore in which is secured the outer end portion of a fine long cleaning wire or needle 21 the inner end of which is tapered to a fine point so as to readily enter the opening of burner 8, the needle being disposed substantially coaxial with this opening as illustrated. Movement of member 17 in either direction is limited by a pin 22 secured in valve 13, the inner end of this pin projecting into a groove 23 in the outer face of member 17. By reciprocating member 17 the cleaning wire 21 may be caused to enter and effectually clean out and open the fuel opening of burner 8 and, as the wire is much smaller than this opening, this cleaning out of the fuel opening of burner 8 may be performed while the torch is in use without materially interfering with the amount of flame and heat produced. A valve and cleaning means similar to those described are provided for regulating the flow of fuel to, and cleaning, the pilot valve 9.

The bottom 24 of tank 1 is concaved to accommodate the head of a plug 25 threaded into a valve casing 26 secured through bottom 24 centrally thereof. This casing is provided with a web 27 which is centrally apertured and ground to provide a seat for a ball valve 28 normally held seated by a coil spring 30 confined between the valve and the false bottom 24^a, said false bottom being provided with a central aperture 32 through its top. A valve casing 33 is secured through the top of the tank and is provided with a bore 34 through its lower end, this bore communicating with a valve chamber 35 in which is mounted a ball valve 36 for normally closing the upper end of the bore. This valve is held seated by a coil spring 37 the upper end of which presses against a plug 38 threaded in the upper end of casing 33 and provided with an axial bore 39, this

plug being secured in adjustment by a jamb nut 40 so as to vary the pressure exerted by the spring on the valve to suit conditions.

Tank 1 is provided with a suitable handle 42 the upper end of which is attached to the tank by a member 43. The lower end of the handle fits into a socket 44 carried by a tubular member 45 secured through the peripheral wall of the tank and provided with an axial duct 46 in its inner end portion. The outer end of this duct is normally closed by a valve 47 threaded into member 45 which is also provided with a radially extending duct 48 communicating with the space 49 about the point 50 of the valve. By opening the valve, the gas may be permitted to escape under pressure through duct 48. This provides means for readily determining if there is any gas in the tank, and also for determining if any of this gas is in liquid form so that the advisability or necessity of renewing the supply of gas can be ascertained.

The tank 1 is provided with a false bottom 24^a which fits tightly about the upper end of valve casing 26, the space between the bottom 24 and false bottom 24^a forming a gas chamber 51. A tube 52 has its lower end secured through false bottom 24^a, the lower portion of this tube being provided with perforations 53. A thimble 54 is threaded upon the lower end of the tube and is provided with a central opening ground to provide a seat for reception of the point of a needle 55 which extends through the tube and is slideable through a packing gland 56 secured on the upper end of the tube which also extends through the top of the tank. A tube 57 is secured in one of the auxiliary ducts of standard 2 and communicates at its lower end with chamber 51, and a tube 41^a is secured in the other auxiliary duct. By opening valve 55 the gas in liquid form may be permitted to drip into chamber 51 where it quickly becomes gaseous. The gas thus produced may be fed to the burner, by means of tube 57, and the liquefied gas or fuel may be supplied to the burners by means of tube 41^a, as will be understood.

50. In practice, the gas in liquid form is introduced into the tank through valve casing 26, plug 25 being removed for this purpose and replaced when the desired amount of liquefied gas has flowed into the tank. By 55 opening valve 7, valve 6 being closed, the gas in liquid form may be supplied to either one or both of the burners, as desired, and by reversing this operation the gas in its gaseous form may be supplied to the burners.

60. To permit ready flow of the fuel to the main burner 8 in the event that the valve for the pilot burner is closed, duct 5 is provided with an enlargement or chamber 5^a forming a by-pass about the valve body, and a simi-

lar chamber 5^b is provided at the upper end 65 of the duct to accommodate the nose or point portion of valve 13.

As suggested herein, there may be changes made in details of construction and arrangement of different parts of the invention 70 without departing from the field and scope of the same, and I intend to include all such variations, as fall within the scope of the appended claims, in this application in which a preferred form only of my invention is disclosed.

What we claim is:—

1. In a torch of the character described, a fuel tank provided with a double bottom; the fuel contained in said tank being in a 80 liquid state in the upper chamber of said tank and in a gaseous state in the lower chamber comprised within said double bottom.

2. In a torch of the character described, 85 a fuel tank provided with a double bottom; the fuel contained in said tank being in a liquid state in the upper chamber of said tank and in a gaseous state in the lower chamber comprised within said double bottom and means to introduce liquid fuel from the upper chamber into said lower chamber.

3. In a torch of the character described, 95 a fuel tank provided with a double bottom; the fuel contained in said tank being in a liquid state in the upper chamber of said tank and in a gaseous state in the lower chamber comprised within said double bottom and adjustable means to introduce liquid fuel from the upper chamber into 100 said lower chamber.

4. In a torch of the character described, a tank adapted to contain a liquefied fuel gas, and provided at its lower end with a gas chamber, means for permitting the liquefied 105 gas to drip into said chamber so as to produce gas in gaseous form therein, a burner, and means for supplying fuel to said burner from said gas chamber or from within the body of the tank adjacent the bottom there- 110 of, optionally.

5. In a torch of the character described, a tank provided with a double bottom, the upper part of said tank adapted to contain liquefied gas, means for permitting the liquefied gas to drip into said lower part of the tank, so as to produce gas in gaseous form therein, a burner, means supplying fuel to said burner from said gas chamber or from within the body of the tank adjacent the bottom thereof, optionally and a self closing valve centrally located at the bottom of the tank.

In testimony whereof we affix our signatures.

CHARLES H. ALLEN.
JAMES B. ANDERSON.
